CLAIM

The ornamental design for a baluster connector, as shown and described.

DESCRIPTION

FIG. 1 is a top perspective view of the baluster connector;
FIG. 2 is a bottom perspective view of the baluster connector;
FIG. 3 is top view of the baluster connector;
FIG. 4 is a bottom view of the baluster connector;
FIG. 5 is a left side view of the baluster connector;
FIG. 6 is a right side view of the baluster connector;
FIG. 7 is a front side view of the baluster connector; and,
FIG. 8 is a rear side view of the baluster connector.

The broken lines are shown for the purpose of illustrating portions of the connector and form no part of the claimed design.
